E. B. THURSTON

ELEVATOR CONTROL SYSTEM

Filed Dec. 10, 1921

UNITED STATES PATENT OFFICE.

ERNEST B. THURSTON, OF TOLEDO, OHIO, ASSIGNOR TO THE HAUGHTON ELEVATOR & MACHINE COMPANY, OF TOLEDO, OHIO, A CORPORATION OF OHIO.

ELEVATOR-CONTROL SYSTEM.

Application filed December 10, 1921. Serial No. 521,533.

This invention relates to the control of electric equipment.

This invention has utility in connection with the operation of a driven member in 5 limited regions, as, in a terminal region for making an elevator move to a landing where the limit or other switch may interfere with normal stopping.

Referring to the drawing:

10 The figure is a wiring diagram of an embodiment of the invention in connection with an alternating current three phase motor circuit for elevator operation and control.

The phase alternating current motor 1 is 15 shown as having shaft 2 carrying brake drum 3 normally set by spring 4. This motor shaft 2 has worm 5 thereon for speed reduction driving of worm wheel 6 actuating drum 7 carrying cable 8 to elevator 20 car 9 for causing said elevator car travel as to landings 10 in elevator shaft 11. This elevator hoisting cable 8 extending past the hoisting drum 7 passes over idler 12 to counterweight 13.

25 In the elevator car 9 is a remote control device for operating the motor 1. This remote control apparatus or controller 14 has contact 15 engaging medial terminal 16 having line 16' extending to power supply line 30 17. By shifting the controller 14 for up-direction travel of the elevator car 9 in the elevator shaft 11, such contact 15 of the controller will move over to contact 18 in communication by line 19, with normally 35 closed upper final or stopping switch 20, thence by line 21 to energize coil 22 of up direction switch 23, thence by line 24 through safety devices such as car door interlock, landing door interlock, over-travel switches, 40 etc., thence by line 25 to power supply line 26, thereby completing a phase for energizing this coil 22 and closing up-direction switch 23.

Power may be supplied from the line 17 45 through this switch 23 by way of line 27 to coil 28 of the slow speed winding of the motor 1. This line 27 has branch 29 to coil 30 of slow speed main switch 31, thence by line 32 through interlock 33 at main high speed switch 34. This interlock 33 is closed when such high speed switch 34 is open. From 50 this interlock 33 the current is conducted by lines 35, 36, to the up-direction switch 23 which by way of line 37 is connected with

the supply line 26. Accordingly, simultaneously with the energizing of the up-direction switch 23 there is energizing of slow speed main switch 31.

This main slow switch 31 is connected back of the direction switch 23 which has line 38 therefrom to this switch 23 and there connected to line 39, through resistances 40, 41, 42, and line 43 to coil 44 in the slow speed primary winding of the motor 1. Third power supply line 45 is connected by this slow speed main switch 31 with line 46 through resistances 47, 48, 49, and thence by line 50 in connection with coil 51, thereby completing the three connections to the coils 28, 44, 51, of the slow speed winding of the 70 motor 1, and energizing such winding for slow speed operation of the motor 1 with all the resistances in series.

Simultaneously with this energizing of the motor 1 for slow speed operation, the brake 75 drum 3 is released. From the line 38 extends line 53, to brake coil 54 operable against the action of the spring 4 to release the drum 3, thence by lines 55, 56, to the line 27.

Upon the closing of the direction switch and throwing in of the main slow speed switch, there also occurs operation of a third switch. The line 39 has branch line 57 to coil 58 of slow speed acceleration switch 59, 85 thence by line 60 to the line 46. As this switch 59 is closed, line 61 from the line 57, is connected to line 62, cutting out the resistance 40, and also, line 63 from the line 60 is connected to line 64 cutting out the 90 resistance 47. The cutting down of the resistance in starting accordingly has a slight mechanical lag behind the closing of the main slow speed switch 23.

The controller 14 may now be shifted to have its contact 15 upon terminal 65, as desired to speed up the motor 1 from the slow speed of operation to high speed operation. This contact 65 is connected with line 66 extending through upper slowing down limit switch 67, thence by lines 68, 69, to coil 70 of the high speed switch 34, thence by line 71 to the line 24, and through the safety devices for completing a circuit in energizing the main high speed switch coil 70. Throwing of this main high speed switch 34 by lifting the contact 33, deenergizes the 105 main slow speed switch 31, and thereby

automatically cuts out the slow speed winding coils 28, 44, 51. Simultaneously the power supply line 45 through line 72 is connected with line 73 and high speed winding 5 coil 75.

The power line 38 has branch 76 to the switch 34, which from thence extends by line 77 to coil 78 of the high speed winding of the motor 1. The line 56 is connected to 10 the third coil 79. Accordingly the three coils 75, 78, 79, of the high speed primary winding of the motor 1 are now energized. In normal operation of the motor 1 the controller 14 may be thrown so that this high 15 speed winding is in at once at starting without the intermediate low speed. There is thus obtained greater starting torque than on the slow speed normal acceleration.

With the motor under way in operation of 20 the high speed winding 75, 78, 79, further shifting of the controller 14 to contact 80 brings no results, for line 81 therefrom is to interlock 82 held open by the throwing of the main high speed switch 34 into 25 operative position. However, if a switch be open, say the slowing down limit switch 67, this main high speed switch coil 70 is de-energized and the switch 34 is accordingly opened, bringing the interlock 82 down into contact 30 position for line 81. When this switch 34 is de-energized by the opening of the switch 67, this does not de-energize or preclude complete current for the coil 30 at the slow speed main switch 31. Accordingly, in 35 throwing this switch 67 say by travel of the car 9 past such switch there is merely de-energizing of the coils 75, 78, 79, of the high speed winding of the motor 1. If the controller 14 be left in control position up to 40 and including the terminal 65, the motor 1 may be operated upon the slow speed winding 28, 44, 51.

The torque of the slow speed winding is less than that of the high speed winding and 45 with a heavy load upon the elevator car 9 it may not be possible to shift the load say to get an exact landing position, while the winding 28, 44, 51, has resistances in series therewith for the desired normal acceleration and control. However, this difficulty 50 may be cured by shifting of the controller 14 to contact 80 which, through the line 81 and the interlock 82 may have connection by line 83 to energize coil 84 of switch 85. The line 86 from this coil 84 extends to the line 71 connected through the safety devices for completing the circuit of the coil 84 at 55 the switch 85.

Throwing of this switch 85 connects line 60 87 between resistances 48, 49, with line 88 connected to the line 64, thereby cutting out the resistances 47, 48, of the slow speed winding. Simultaneously, line 89 between resistances 41, 42, is connected by way of 65 line 90 to the line 62, thereby cutting out the

resistances 40, 41. With this substantial reduction in the resistance of the slow speed winding for this motor 1, there is such proportional increase in the torque that the load which the elevator car may be designed 70 to handle, may be taken care of for the short distance of travel as desired in the limit stop region as effectively by the low speed winding as by the high speed winding, while preserving the desired features of control in 75 other operation of the car. This control is determined by the position of the car in the region of a limit, and therefore is independent of the car speed but has to do with car position.

The operation as described for the up-direction travel correspondingly applies in down-direction travel by shifting of this controller 14. The windings 28, 44, 51, are accordingly of one speed or low speed for 80 the motor 1, and the windings 75, 78, 79, are accordingly for a second or higher speed of the motor 1. The brake coil 54 is operative, regardless of which winding is in for driving.

For availing of advantages in electromagnetic or generator action in stopping the car, the operator may hold the controller 14 so that its contact 15 is over at least as far as contact 65 when the car is within the 85 region of the slow-down switch 67 but had not opened the final limit switch 20. If the car be at intermediate position in the hatchway from the limit switch, for this generator action of braking the controller should 90 not be further over than the terminal 18. There is, accordingly, within the control of the operator of the car a generator action braking in stopping the car due to the interlock on the open high speed switch interlock 100 33 on the main high speed switch. This interlock 33 not only closes the slow speed switch 31 but keeps resistance in series with the slow speed winding so that the slow speed winding is loaded. Accordingly, as 105 long as the motor 1 rotates above the synchronous speed of the windings 28, 44, 51, there is a little magnetic braking or loading resisting the operation of such motor 1 and this action is independent of the operation 110 of the spring 4 on the brake drum 3, for as long as the controller 14 is in position to permit this loading of the motor 1 by the winding 28, 44, 51, the brake coil 54 is energized. For final stopping of the motor 1, it is in order to throw the controller 14 115 to central or off position.

What is claimed and it is desired to secure by Letters Patent is:

1. An elevator, a motor therefor having 120 low and high speed windings, resistance in series with the low speed winding, cut out means for the high speed winding and a controller provided with connections extending to connect differently as to resistance for 125 130

low speed winding motor acceleration when the high speed winding is cut out by said means than when said cut-out means is in.

2. An elevator, a motor therefor having a low speed primary winding and a high speed winding, resistance in series with the low speed primary winding, cut out means for the high speed winding, and connections for changing the resistance to increase the low speed winding torque when the cut out means has operated, said connections including a controller shiftable to control generator braking action of the low speed winding.

3. In electrical power equipment, a controller, a motor, a set of switches and resistances for automatically bringing the motor through a series of speeds in timed sequence into a predetermined final speed, and another switch for putting the motor into a different final speed, the actuation of said last mentioned switch operating to automatically return said set of switches to initial position.

4. In electrical power equipment, a controller, a motor having a plurality of windings which will operate at a plurality of different speeds, a set of switches and resistances controlled thereby associated with one of said windings, and control circuits operative to position said switches in a predetermined initial condition when the controller is not in the position for actuating them.

5. An elevator, a motor therefor, a resistance for the motor, slow down and stop limit switches for the elevator, a controller on the elevator for the motor, and connections from the controller, rendered effective by the opening of the slow down switch by the elevator, for cutting said resistance in or out at will while the motor is still connected.

6. An elevator, a motor therefor, a resistance for the motor, slow down and stop limit switches for the elevator, a controller on the elevator for the motor, a slow down switch device, and connections from the controller, rendered effective by the elevator opening said slow down switch, for coaction through said device for cutting said resistance in or out at will while the motor is still connected.

7. An elevator, a motor therefor, a resistance for the motor, a stop switch, a slow down limit switch directly adjacent thereto to be operated by elevator travel, a controller on the elevator for the motor, the normal control of the motor by the controller being limited to a restricted range of controller operation by the limit switch, and a resistance connection device, said device being rendered operative by the opening of said slow down switch by the elevator, and said device being controllable by the movement of said controller beyond its restricted

normal range to cut in or cut out said resistance at will.

8. An elevator, an alternating current motor for actuating the elevator, said motor having a plurality of synchronous speeds, a limit switch controlled by the position of the elevator, a controller, connections from the controller normally available to cause the motor to approach its lowest synchronous speed, and other connections from the controller, rendered available by the operation of the limit switch, for increasing the tendency of the motor to approach its lowest synchronous speed during the travel of the car beyond and away from the point where the limit switch is operated.

9. A two speed alternating current electric motor, a current supply for said motor, control connections for high and low synchronous speed operation of the motor, a limit switch device for cutting out the high speed motor connection, a resistor in the low speed motor connection, and a controller operable independently of motor speed and effective at will, when the high speed motor operation connection is cut out by said switch device, to lessen the effect of the resistor in the low speed motor connection during further travel in the same direction.

10. A polyphase alternating current electric motor provided with a low speed primary winding and a high speed winding, control connections for the windings, resistance in series with the low speed connection having a portion thereof maintained in circuit when the motor is normally operating at low speed, a limit switch for cutting out the high speed winding, and a controller shiftable to a position normally bringing about high speed operation of the motor, but effective by operation of the limit switch and for continued operation in the same direction, to reduce the resistance in series with the low speed winding.

11. A multi-speed alternating current motor, control connections for varying the speed of the motor, a limit switch device for cutting out high speed operation of the motor through said connections, means for modifying the current flow through the motor, and a controller shiftable to a position where it is effective, by operation of the limit switch and for continued operation in the same direction, to change the current flow modifying means in the low speed motor operation connection to increase the tendency to approach lower synchronous speed of the motor.

12. An elevator, an alternating current motor therefor having high and low synchronous speed windings, a limit safety cut-out for the high speed winding, resistance coacting with the low speed winding and having a portion thereof maintained in circuit when the motor is normally operating

at low speed, and a controller provided with connections for the high and low speed windings and operable at will, when the cut-out is opened, to increase the tendency of said motor to approach low synchronous speed by reducing said resistance during further elevator travel in the same direction after the limit switch is opened.

18. An elevator, an alternating current electric motor therefor having high and low synchronous speed windings, a current supply for said windings, control connections for the winding, a limit safety device automatically operable by elevator travel in a determined range for cutting out said high speed winding, a resistance in the low speed winding having a portion thereof maintained

in circuit when the motor is normally operating at low speed, said resistance being effective in motor stopping for load generator operation of said motor in generating current back into said current supply, and a controller, precluded by said connections from modifying said resistance when the high speed winding is in, but effective through said connections, when said safety device has cut out the high speed windings, for reducing said resistance and thereby increasing the starting torque of the low speed motor for causing the motor to approach its lower synchronous speed in handling the load of the elevator.

In witness whereof I affix my signature.

ERNEST B. THURSTON.
